CORSET

Otto D. Mowry, Evanston, Ill., assignor to I. Newman & Sons, Inc., New Haven, Conn., a corporation of Connecticut

Application August 22, 1935, Serial No. 37,389

7 Claims. (Cl. 2-30)

This invention relates to corsets and has for an object to provide an improved construction wherein the same merges into a brassière structure formed to uplift the breasts and remain firmly in position without the use of shoulder straps.

Another object of the invention is to provide a corset having a corset body and a brassière section or formation with constricting and slideable means for holding the brassière section in the desired functioning position while permitting ready flexing of the body in any direction.

An additional object of the invention is to provide a corset having a brassière section carried and supported by the corset body without the use of shoulder straps, and means for automatically adjusting the side and top line of the brassière as well as under the arms and back so that the desired support and fit is secured at all times.

A further object, more specifically, is to provide a corset having a brassière portion wherein the breast pockets are supported through the use of wire or similar stiffening members positioned to substantially surround the pockets and arranged with a sliding supporting bar or section extending between the breast pockets and slidably mounted in a pocket of the corset body so that the desired support and the desired flexibility are secured.

In the accompanying drawing—

Figure 1 is a front view of a corset disclosing an embodiment of the invention;

Fig. 2 is a rear view of the corset shown in Fig. 1;

Fig. 3 is a fragmentary sectional view through Fig. 1 on the line 3—3;

Fig. 4 is an elevation of the reinforcing and supporting member illustrated in Fig. 1;

Fig. 5 is a view similar to Fig. 4 but showing a slightly modified construction of supporting member.

Referring to the accompanying drawing by numerals, 1 indicates a corset body which is shown of the step-in type and which is provided with a slide fastener 2 at the rear extending from the top of the rear part of the brassière section 3 and downwardly to a point below the waistline. If desired, suitable stiffening boning or stay members may be arranged in the pockets 4 and 5, said pockets being arranged at or adjacent the sides of the garment.

It will be noted that the garment is not supplied with shoulder straps and, consequently, the brassière section 3 is not only carried by the cor-

set body 1, but the various parts are supported in proper position without the use of shoulder straps, which result is secured through the use of a supporting member 6 which, as shown in Fig. 4, is formed from wire and is bent to provide the respective loops 7 and 8 and a central section 9 adapted to slide freely in the pocket 10.

In the form shown in Fig. 5 the same structure is present except that the loops 7 and 8 are secured by welding or otherwise at 11 a flat piece 10 of metal 12 which takes the place of the section 9 when the device is in use. The support 6 is arranged so that the section 9 is in the pocket 10, while the loops 7 and 8 are fitted into the hems or sockets 13 and 14 of the respective breast pockets 15 and 16. The loops 7 and 8 are sufficiently long to completely encircle the upper half of the breast pockets and then extend around the center of the back under the arms, as shown in Fig. 2, and therefore present a bendable and also resilient support for the pockets and for the breasts when the garment is in use. In this way the body of the person wearing the garment is supported and constricted by the corset body 1, while the breasts are supported by the brassière without the use of shoulder straps.

The brassière at the front is really an extension of the corset body, while at the sides and rear there are provided elastic sections or panels 17 and 18, to which are secured diagonal panels 19 and 20. These panels are formed of Lastex or other elastic material. By reason of the position of the panels 19 and 20, which gives a diagonal pull, the sides and upper part of the breast pockets are automatically adjusted. This automatic adjustment of the top line of the brassière and under-arm adjustment of the corset, is through the action of these Lastex or elastic members pulling diagonally or obliquely on the center back toward the under-arm portions or panels 17 and 18. By reason of the structure just described, the breast pockets are supported from above, which as shown in Fig. 2 means are provided for supporting these pockets from below. These means consist of reinforcing stays 21 and 22 which may be of wire, metal, or other material, arranged in the respective pockets 23 and 24 forming the bottom edge portion of the breast pockets. Diagonal stays 25 and 26 are arranged in pockets 27 and 28 and act to support the stays 21 and 22, said diagonal pockets merging into the pocket 10 and the diagonal braces 25 and 26 braced against the pocket 10 and the section 9 which it contains. In this way a three-point suspension is secured. It will be observed that

the pockets are secured on the lower edge portion and by reason of the supporting element 6 they are supported by a continuous one-piece member at the top with a part extending over the dia-
5 phragm, said latter part sliding in the pocket 10 in case the person wearing the corset should bend toward the front.

10 The body 1 may be made of substantially inelastic material, or, if preferred, the front could be made somewhat elastic longitudinally and the back somewhat elastic circumferentially.

I claim:

- 15 1. A garment of the character described including a corset body and a brassière, the corset body and brassière at the back being open, the opening in the corset body extending to a short distance below the waistline, disengageable fasteners for drawing the corset body and brassière together at said opening, said brassière being provided with a pair of breast pockets, and a supporting structure therefor, said supporting structure including a straight section extending between the breast pockets downwardly to overlap the corset body, a pocket carried by the brassière 25 and corset body guiding said section, and integral loops extending from said section, said loops extending around the upper edge of the breast pockets under the arms and to the center of the back to a point adjacent the top of said openings, and 30 a pocket for each of said loops, said pockets forming the upper portion of the respective breast pockets at the top and merging into the upper edge of the brassière under the arms and back.
- 35 2. A garment of the character described including a corset body and a brassière merging together, said brassière being formed with a pair of breast pockets, and means partly carried by the brassière and partly by the corset body presenting independent supports for the pockets at the lower edge and a support for each of the pockets at their upper edges, said support comprising a looped wire connected to the upper edge of each pocket and partly encircling the pocket and a central supporting bar merging into the respective wires encircling said pockets, whereby the pockets are supported without the use of shoulder straps.

- 50 3. A garment of the character described including a corset body and a brassière, said brassière having a pair of breast pockets, said brassière being cut low at the back, the back gradually merging into the sides and the breast pockets at the front, and a resilient reinforcing member having a pair of loops, said reinforcing member 55 also having a straight section extending between the breast pockets downwardly and the loops fitted over the upper part of the breast pockets and extending along the edge of the brassière to the center of the back, said brassière being 60 formed with pockets for receiving the loops where-

by the loops will act to support the upper edge of the brassière including the breast pockets.

4. In a garment of the character described including a corset body and a brassière, a reinforcing member for the upper edge of the brassière 5 comprising a support having a straight section extending downwardly centrally of the front of the brassière and said body and a pair of diverging loops integral with said straight section positioned to extend around the upper edge of the brassière 10 for supporting the same.

5. A combined corset and brassière, comprising a corset body section and a brassière section, said brassière section having a pair of breast pockets, a reinforcing and stiffening member of metal ar- 15 ranged at the lower part of each breast pocket, a reinforcing and stiffening stay for supporting said reinforcing members, said stays being arranged diagonally, and a metallic supporting member for the upper part of the breast pockets 20 and the upper edge of the side and rear of the brassière section, said supporting member including a pair of metallic loops and a central straight section.

6. A step-in corset comprising a body and a 25 brassière having breast pockets, said brassière merging into said body at the upper edge of the body, said body being open at the back from the upper edge downwardly for part of the length of the corset, said brassière having at the rear a 30 pair of diagonally arranged elastic members acting to give a diagonal downward pull on the end portions of the brassière, a slide fastener for disengageably securing the elastic sections together and also the opening in the back of the corset 35 body, and stiffening and supporting means for said breast pockets, said stiffening and supporting means including an arc-shaped bar at the lower edge of each of said pockets, a diagonally positioned bracing bar for each arc-shaped bar, 40 and a vertically positioned bar carried by the front of the corset body at the center thereof, said vertically positioned bar merging into two loops at the upper end, said loops being slidably connected to the upper edges of the respective 45 breast pockets.

7. A garment of the character described, including a corset body and a brassière, said brassière including a pair of breast pockets, an arc-shaped stiffening member at the lower edge of 50 each pocket for supporting the respective pockets at the bottom portion, a diagonally arranged stay bar engaging each of said stiffening members, and a partly encircling sliding stiffening member for each of said breast pockets supporting the pockets at the upper edge thereof, said last-mentioned stiffening members being anchored centrally of the upper part of the garment.
